[57] CLAIM

The ornamental design for a telephone stand or similar keyboard article, substantially as shown and described.

DESCRIPTION

FIG. 1 is a perspective view of a telephone stand or similar keyboard article embodying our new design;
FIG. 2 is a top view taken perpendicular to the face of the article;

FIG. 3 is a side view thereof;

FIG. 4 is a front view thereof; and

FIG. 5 is a rear view thereof.

The broken line showing a handset cradle is for illustrative purposes only.

FIG. 1

FIG. 2

FIG. 3

FIG. 4

FIG. 5
